SWING

Herbert S. Rice, Clifftondale, Mass., assignor to
Ethel M. Rice, Saugus, Mass.

Application October 15, 1931, Serial No. 568,993

9 Claims. (Cl. 155—62)

This invention relates to swings and particularly to devices of this character intended for use on lawns and in playgrounds.

The object of the invention is the provision of a swing which will hold one or more persons, which will be simple and strong in construction and which may be safely used by very small children.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings

Figure 1 represents a front elevation of a swing embodying the principles of the present invention.

Figure 2 represents a side elevation of the lower end of said swing.

Figure 3 represents a horizontal section on line 3, 3, on Fig. 2.

Figure 4 represents a horizontal section on line 4, 4, on Fig. 2.

Figure 5 represents a side elevation of the upper end of the swing.

Figure 6 represents a front elevation thereof.

Figure 7 represents a horizontal section on line 7, 7, on Fig. 6, a small portion being shown in plan.

Figure 8 represents a vertical section on line 8, 8, on Fig. 7.

Figure 9 represents a section on line 9, 9, on Fig. 6, and

Figure 10 represents a plan of one of the spring caps.

Similar characters indicate like parts throughout the several figures of the drawings.

In the drawings, 10 is a pipe forming a part of the usual supports used in public playgrounds.

Depending from this support 10 are two separated hangers 11 formed in two parts and clamped together by bolts 12.

To insure against movement on the support 10, the hangers 11 have set screws 13, the inner ends 50 of which impinge upon the periphery of the support 10 and lock the hangers in position.

Between the hangers 11 is disposed a tubular member 14 having a downward extension 15 in which is a socket 16 to receive the upper end of a wooden bar 17.

This bar is secured in position in the socket 16 by means of bolts 18 having thumb nuts 19 threaded thereto, as shown in Figs. 5 and 6 of the drawings.

Secured to the under face of ears 20 forming part of the hangers 11 are cross plates 21.

Through each cross plate and midway between the hangers 11 is a bolt 22 having a head 23 at its lowest end and a nut 24 threaded to the opposite end.

Between the under face of the plate 21 and the head 23, the bolt 22 is surrounded by a helical spring 25, the opposite ends of which are positioned in annular washers 26, as shown in Fig. 9 of the drawings, said washers being secured to the spring 25 by means of ears 26x shown in Fig. 10.

The extension 15 of the member 14 is provided on opposite faces with bosses 27, which during the movement of the member 14 contacts with the heads 23 of the bolts 22 and limit the movement of the members 14, 15 about the axis of its pivotal connection with the hangers 11.

This pivotal connection consists of a cylindrical member 28 within the tubular member 14.

The opposite ends of member 28 are reduced in diameter as at 29 and these reduced ends are surrounded by annular collars 30 having peripheral grooves to receive a plurality of anti-friction members 31, said members 31 extending into grooves in the annular members 32 at the opposite ends of said tubular member 14.

The member 28 has oppositely extending threaded shanks 33 which project through holes in the hangers 11 and have clamping nuts 34 secured to the outer ends thereof.

These nuts 34 may be turned sufficiently to clamp the hangers 11 against the outer faces of the reduced ends 29 of the member 28 so that said member 28 cannot rotate about its axis.

Between the inner cylindrical face of the tubular member 14, and the periphery of the member 28, there is a chamber 35 which is filled with lubricant, this lubricant being introduced into said chamber by removing the threaded plug 36 in the upper end of member 14.

Owing to the anti-friction members surrounding the reduced ends 29 and the lubricant introduced into the chamber 35 surrounding the member 28, the member 14 will freely oscillate about the axis of the member 28, and all deviation from the vertical plane is entirely prevented.

The lower end of the bar 17 has a metal strap 37 secured thereto at 38 with its opposite ends 39 bent downwardly to form a triangle and said ends 110

39 are secured to the opposite faces of the bar 17 at 40.

Secured to the upper face of the horizontal portion of this strap 37 are two oppositely disposed seats 41 preferably of saddle shape, as shown in Fig. 3 of the drawings.

Secured to opposite faces of the bar 17 at a point above the seats 41 are elongated handles 42, the vertical portions of which are surrounded by 10 resilient closures 43.

These resilient closures 43 afford a yielding grip for the occupants of the swing and the vertical portions of these handles are of sufficient length to be seized by either a small or large 15 child.

The bar 17 also has secured to opposite faces of its extreme lower end metal plates 44 to which are secured oppositely disposed U-shaped stirrups 45 by bolts 46.

20 These stirrups 45 are formed in such a manner as to give upper and lower footrests to accommodate children of different sizes.

The vertical portions of these stirrups 45 are surrounded by resilient closures 47 as a safety 25 precaution to prevent injury to children in case they get in the path of the swing and are hit thereby.

It will be noted that the swing will always move in the same vertical plane and there is no possible 30 chance for deviation therefrom owing to the construction of the pivotal connection with the fixed hangers 11.

By providing the shock absorbers 25 the movement of the swing in either direction is limited 35 and when either of the bosses 27 come into contact with the bolts 22, 23, the springs 25 will yield and gradually stop further movement in that direction.

At the end of the playground season it is desirable 40 to store the lower part of the swing for the winter months and install it again in the spring.

This can easily be accomplished by removing the bolts 18 and then removing the bar from the socket 16.

45 This swing is very strong, may be easily installed, and is safe for use by even very small children.

It is believed that the operation and many advantages of the invention will be understood without further description.

Having thus described my invention, I claim

1. A swing comprising a support provided with depending hangers; a member between and pivoted to said hangers having a socket in its lower 55 end; a single continuous bar the upper end of which is secured in said socket; a seat on the lower end of said bar; cross plates between said hangers; a pin movable endwise in each plate and extending downwardly therefrom with a shoulder at its lower end; and a spring surrounding said pin between said plate and shoulder.

2. A swing comprising a support provided with depending hangers; a member between and pivoted to said hangers having a socket in its lower 65 end; a single continuous bar the upper end of which is secured in said socket; a seat on the lower end of said bar; cross plates between said hangers; a pin movable endwise in each plate and extending downwardly therefrom with a shoulder at its lower end; a spring surrounding said pin between said plate and shoulder; and means for regulating the tension of said springs.

3. A swing comprising a support provided with 75 depending hangers; a member between and pivoted to said hangers having a socket in its lower

end; a single continuous bar the upper end of which is secured in said socket; a seat on the lower end of said bar; cross plates between said hangers; a pin movable endwise in each plate and extending downwardly therefrom with a shoulder at its lower end; a spring surrounding said pin between said plate and shoulder; and bosses on said member adapted to coact with the lower ends of said pins to limit the oscillation of said member.

4. A swing comprising a support provided with two separated depending hangers, each hanger being independently clamped to said support; a member between and pivoted to said hangers having a vertical rectangular walled socket in its lower end; a single continuous rectangular bar the upper end of which is fitted to and secured in said socket; two oppositely disposed seats wholly supported on the lower end of said bar; and spring buffers mounted on and extending downwardly from said hangers adapted to coact with said member to limit its upward oscillation in either direction.

5. A swing comprising a support consisting in part of a horizontal pipe; two separate depending two-part hangers; means for clamping the two parts of each hanger to said pipe; set screws in the upper part of said clamping members impinging on said pipe; a member between and pivoted to said hangers having a vertical rectangular walled socket in its lower end; a single continuous rectangular bar the upper end of which is fitted to and secured in said socket; and two oppositely disposed seats supported on the lower end of said bar.

6. A swing comprising a support consisting in part of a horizontal pipe provided midway its length with two separated depending hangers, each hanger being independently clamped to said pipe; a member between and pivoted to said hangers having a vertical walled socket in its lower end; a single continuous bar the upper end of which is secured in said socket; and seating means at the lower end of said bar.

7. A swing comprising a support consisting in part of a horizontal pipe provided midway its length with two separated depending hangers, each hanger being independently clamped to said pipe; a member positioned between said hangers having a vertical walled socket in its lower end and an elongated cylindrical hole in its upper end; a pivot pin extending through said hangers and hole and having threaded ends extending a short distance beyond said hangers; clamping nuts on said threaded ends; a single continuous bar, the upper end of which is fitted to and secured in said socket; and seating means at the lower end of said bar.

8. A swing comprising a support consisting in part of a horizontal pipe provided midway its length with two separated depending hangers, each hanger being independently clamped to said pipe; a member positioned between said hangers having a vertical walled socket in its lower end and an elongated cylindrical hole in its upper end; a non-rotatable pivot pin extending through said hangers and hole and provided with an enlarged portion, the ends of which abut the inner faces of said hangers; a single continuous bar, the upper end of which is fitted to and secured in said socket; and seating means at the lower end of said bar.

9. A swing comprising a support consisting in part of a horizontal pipe provided midway its length with two separated depending hangers,

each hanger being independently clamped to said pipe; a member positioned between said hangers having a vertical rectangular walled socket in its lower end and an elongated cylindrical hole in its upper end; a pivot pin in said hole provided with reduced ends extending through and clamped to said hangers to prevent rotation thereof; a re-

movable single continuous rectangular bar, the upper end of which is fitted to and disposed in said socket; bolts extending through said member and bar for securing said bar in position; and seating means at the lower end of said bar. 80
